WEDGE

Earl H. Harmon, New Hartford, N. Y., assignor
of one-half to William G. Pope, Utica, N. Y.

Application May 15, 1936, Serial No. 79,952

6 Claims. (Cl. 306—33)

My invention relates to a wedge and I declare the following to be a full, clear, concise and exact description thereof sufficient to enable any one skilled in the art to which it appertains to make and use the same, reference being had to the accompanying drawing in which like reference characters refer to like parts throughout the specification.

The object of the invention is to provide a wedge for use more particularly in securing hammer or axe heads to their respective handles. The shock incident to the use of the aforesaid tools has caused the wedges heretofore used to work loose and thereby allow the head of the hammer or of the axe to separate from its handle and this perhaps at a time when the hammer or axe is being swung to drive home a nail or in the case of the axe to split wood with accompanying fatalities. The present wedge overcomes these difficulties as will be seen from the drawing in which

Fig. 1 is a perspective view somewhat enlarged showing the wedge.

Fig. 2 is a perspective view somewhat enlarged showing the wedge tipped on one side.

Fig. 3 is a perspective view showing the wedge as it appears from the lower end.

Fig. 4 is a plan view showing a pattern before being bent into shape.

Fig. 5 is a vertical section taken on the line 5—5 of Fig. 1.

Fig. 6 is a plan view looking down on the top of the wedge.

Fig. 7 is a plan view looking in the opposite direction from that of Fig. 6.

Fig. 8 is a perspective view of a hammer broken away and showing the wedge applied thereto.

Referring more particularly to the invention, the wedge consists of a rectangular portion 1 that tapers from its top surface 2 towards its bottom edge 3 in cross section. There is formed integral however, on the opposite sides of the rectangular portion 1 and at its opposite lateral edges, wings 5, 5 by curving the extended part of rectangular central portion 1 at its opposite lateral edges 6, 6 and in different directions, around back upon itself to form additional retaining surfaces. However, each of the wings 5 is spaced from the adjacent surface of central portion 1.

These curved portions 5, 5 do not lay quite parallel with the contiguous opposite lateral surfaces of portion 1 but incline or taper at their free ends 10, 10 towards said respective surfaces.

Moreover, said wings 5, 5 also taper from the

bottom edge 3 toward the top surface 2. The taper, however, is acute at about midway between the bottom edge 3 and top surface 2, whereby said wings 5, 5 disappear or terminate at said central locations. By thus terminating wings 5, 5 below the top surface 2 of portion 1 said wings 5, 5 will disappear in wood 11 of the handle 12 when driven home therein to secure the head 15 to said handle 12.

Furthermore, the taper of central portion 1 from its top surface 2 toward its bottom edge 3 will cause the openings in the grain of the wood 11 of handle 12, made by the entrance of said wings 5, 5 into handle 12, to be closed behind them as they disappear below the upper surface 16 of the end of handle 12. This disappearance of the wings 5, 5 into the wood 11 of handle 12 and the closing of the openings behind them positively locks the wedge 1 into the grain of said wood 11 within the eye or opening 17 of the tool 18, whereby the shock incident to the use of the tool 18 will not allow the wedge 1 to work loose and fall out.

Furthermore, wings 5, 5 although spaced are inclined or tapered laterally towards the respective sides of portion 1 as above stated, whereby to effect inclosing members into which the portions of the wood 11 of handle 12 are driven and inclosed.

This latter inclosure feature and taper has the added advantage of effecting a lateral wedge on either side of central portion 1. These lateral wedges function as the wedge is driven into position into that portion of wood 11 of handle 12 within eye 17 of tool 18 which causes the free points of wings 5, 5 to be forced outwardly thus effecting lateral wedges on opposite sides of part 1 in addition to the wedging of said central portion 1.

As a further means of holding wedge 1 into position when driven home into that portion of wood 11 of handle 12 within eye 17 of tool 18, the free edges of wings 5, 5 are notched or formed with barbs 20 which slide easily into wood 11 of handle 12 but do not allow said wedge 1 to be pulled out of said handle 12.

Having thus described my invention what I claim as new and desire to secure by Letters Patent is as follows:

1. In a wedge, a central portion tapered from one end to the other, wings formed on said central portion, said wings terminating midway between the upper and lower edges of the wedge and disposed on opposite sides thereof, whereby to effect additional retaining members.

2. In a wedge, a central portion tapered from one end to the other, wings formed on opposite sides of said tapered portion and at opposite ends thereof said wings tapering towards said central portion and said wings terminating midway between the upper and lower edges of the wedge, whereby to effect additional wedging functions.
3. In a wedge having a central portion that tapers in cross section from one end to the other, wing members formed on said central portion, said wing members lying in spaced relation to said central portion and tapering towards the same and said wings terminating midway between the upper and lower edges of the wedge, whereby to form pockets to effect additional wedging functions.
4. In a wedge, a central portion tapered in cross section from one end to the other, wings formed on opposite ends of said central portion, said wings lying in spaced relation to said central portion, barbs formed on said wings, to aid in holding them in predetermined position and
5. In a wedge, a central portion tapered from one end to the other, wings formed on opposite sides of said tapered portion, whereby to effect additional wedging surfaces, said wings terminating midway between the upper and lower edges of the wedge, and notches formed on said wings to aid in holding them in predetermined position.
6. In a wedge, a central portion tapered in cross section from one end to the other, wings formed on opposite ends of said central portion, said wings lying in spaced relation to said central portion, barbs formed on said wings, to aid in holding them in predetermined position, and said wings terminating midway between the upper and lower edges of the wedge, whereby they disappear when the wedge is assembled.

EARL H. HARMON.
